UNITED STATES PATENT OFFICE.

HERBERT W. HOOVER, OF NEW BERLIN, OHIO, ASSIGNOR TO THE HOOVER SUCTION SWEEPER COMPANY, OF NEW BERLIN, OHIO, A CORPORATION OF OHIO.

BRUSH-SUPPORTING DEVICE FOR SUCTION-CLEANERS.

1,309,092.

Specification of Letters Patent.

Patented July 8, 1919.

Application filed June 8, 1917. Serial No. 173,447.

To all whom it may concern:

Be it known that I, HERBERT W. HOOVER, a citizen of the United States, residing at New Berlin, in the State of Ohio, have invented a certain new and useful Improvement 5 in Brush-Supporting Devices for Suction-Cleaners, of which the following is a specification.

My invention relates to brush supporting devices for suction cleaners and has for one object to provide a new and improved type of brush support wherein the brush support and the brush adjusting means may all be placed in or withdrawn from the suction nozzle or open mouthed hood as a unit. Another object is to provide such a brush supporting frame as may be placed in or withdrawn from the nozzle by the use of the hands of the operator alone without tools of any kind and whereby the brush supporting means may be held in position without being bolted or riveted or otherwise fastened. Another object is to provide a support whereby the guard fingers which extend across the open mouth of the hood may be kept in proper position with respect to the brush and whereby they may not interfere with the withdrawal of the brush. Another object is to provide means whereby the fingers may terminate at their rear ends short of the rear wall of the open mouth thus permitting the entrance of long particles between the ends of the fingers and the wall of the mouth which otherwise could not be drawn into the system. In this connection means are provided which protect the free ends of the fingers and make it impossible for them to catch under the edge of the rug or other floor covering and which make it impossible for the fingers particularly when the machine is moved backward across the floor to catch any foreign substances. Other objects of the invention will appear from time to time in the specification.

My invention is illustrated more or less diagrammatically in the accompanying drawings, wherein—

Figure 1 is a bottom plan view with parts in section;

Fig. 2 is a section along the line 2—2 of Fig. 1 with the brush removed;

Fig. 3 is a detailed side elevation of a part of the brush supporting frame; and

Fig. 4 is a section along the line 4—4 of Fig. 3.

Fig. 5 is a detail section along the line 5—5 of Fig. 1:

Fig. 6 is a side elevation of the adjusting device.

Like parts are indicated by like characters in all the figures.

A is a hood having an open suction mouth or nozzle A¹, end walls A², A² and communicating by means of a suction passage in the casing A³ with a fan chamber A⁴ which in turn discharges into the exhaust passage A⁵. The fan in the fan chamber not specifically illustrated is of course driven by the usual electric motor and I have only shown that part of the suction cleaner in a very diagrammatic manner as it forms no part of the invention which I am about to describe.

The hood which contains the open suction mouth is provided with flanges B, B¹ about the suction mouth. A brush frame made up of a longitudinal spring cross piece B² upset or ribbed as at B³ for strength and stiffness has at either end a carrying plate B⁴ rigidly mounted on the cross member. This carrying plate is slotted as at B⁵ to engage a lug B⁶ on the outside of the brush adjusting plate B⁷, whereby the brush adjusting plate may be held in adjusted position in the supporting or carrying plate.

C is the brush rotatably mounted by means of bearings C¹ on a shaft C² which shaft is supported at either end on one of the adjusting plates B⁷ so that with the parts shown in the position in Fig. 1 the brush is held and supported free to rotate within the brush supporting frame.

The brush supporting frame is held within the open mouth of the hood by spring fingers D, D at either end of the frame. They are anchored in the upset portions D¹ on the carrying plate B⁴ and yieldingly press the member B² against the front wall of the hood because they engage the rear wall of the hood. These fingers are bent away as at D² to engage lugs D³ in the rear wall of the hood and are provided with finger engaging pieces D⁴ whereby the operator may release the engagement so that he can withdraw the brush frame. The flange B¹ on the front side of the open mouth of the hood prevents the possibility of the brush frame dropping out.

E¹ are hooks stamped out of the brush frame member B² positively disposed in pairs and adapted to hold and position the

spring fingers E^2 E^3 . It will be understood that each pair of spring fingers is joined by a cross-piece which extends between the two hooks and thus when the hooks are bent each over a separate finger this cross piece tying them together furnishes a secure anchorage whereby in cooperation with the member B^2 the fingers are held rigidly in position. These fingers extend rearwardly 10 toward and terminate short of the edge of the flange B that is the rear edge of the open mouth of the hood. They are preferably bent upwardly at their ends and where so bent are in a general way tangential to 15 the brush. The brush is rotated by the belt E^4 driven by any suitable means or as here shown by the motor which drives the fan and the parts are so arranged that looking at the device as in Fig. 2 the brush 20 bristles rotate in a clockwise direction and tend at all times to exert a sweeping influence toward the rear. This prevents any possibility of any foreign matter coming up over the rear ends of the fingers and working 25 toward the front. When the apparatus is moved backward the suction might pick up the edge of the carpet and get it caught over the ends of the fingers but this cannot be done because the brush would immediately sweep away the end of the carpet 30 and compel it to travel under rather than over the ends of the fingers. The same is the case in connection with tassels or fringes on edges of rugs or floor coverings. The gap 35 between the rear wall of the open mouth and the ends of the fingers is provided in order that matches, large pieces of paper or other such refuse may be drawn up into the fan chamber and discharged into the dirt receptacle even though such articles are 40 so long as to be unable to pass between the fingers themselves.

It will be evident that while I have shown 45 in my drawings an operative device, still many changes might be made both in size, shape and arrangement of parts without departing materially from the spirit of my invention and I wish, therefore, that my drawings be regarded as in a sense diagrammatic. 50 The brush adjusting plate B' has a spiral cam groove J in its face. This groove is adapted to engage the boss J^1 on the plate B^4 and when the plate B' is rotated obviously the height of the axis of the brush 55 will be changed on account of the engagement of the cam with the boss. Depressions J^2 in the bottom of the cam are provided to fix and hold the parts against rotation. They must be sprung apart to enable the 60 boss to move from one depression to another and thus a range of adjustment is possible.

The use and operation of my invention are as follows:—

When the parts are in the position shown 65 in Fig. 1, they are ready for operation.

When the operator desires to withdraw the brush and frame, he throws the belt off the pulley. This will enable him to release it from the inner driving pulley driven from the motor. He then pulls back and 70 up on the two thumb pieces to release the spring latches. The springs slide then over the bosses and the brush frame is held in position only by friction. The operator then rotates the brush frame in a counter clockwise direction looking at Fig. 2 until the rear edge comes out of the open mouth of the hood. He is then able to completely withdraw it. This gives him access to the 75 ends of the brush frame to the supporting 80 and adjusting means which are not specifically illustrated. He may then adjust the brush in any manner that he desires, take it out, replace or renew it, change its height 85 or replace the belt and he can then return the brush with the supporting features and apparatus as a unit into the open mouth of the hood. He will do this, of course, by first inserting the forward edge, resting it 90 against the lug or ledge B^1 and rotating 95 it into the position shown on Figs. 1 and 2. He then pushes in on the spring latches of the hood and the apparatus is then in locked position.

The fingers which extend across the open mouth limit the inward movement of the rug or floor covering responsive to the suction toward the brush so that the distance 100 between the covering and the brush acting 105 upon it is fixed. This prevents undue wearing away of the floor covering and of the bristles of the brush. Such fingers are necessary because of the relatively great width of the open mouth necessitated by the presence 110 of the large sized, powerful brush.

Whenever the motor is running and a suction is being created in the nozzle, the brush will be driven so that the free finger ends are always protected when that is 115 needed. If the machine is merely being drawn across the floor with the motor at rest, the upwardly curved rear ends of the fingers will be sufficient to deflect or guide the rug or floor covering so as to prevent 120 its catching on the ends of the fingers.

I claim:—

1. In a suction cleaner a hood having an open suction mouth, a removable brush carrying frame supported within the hood and a rotary brush adjustably mounted on the frame within the hood adjacent the mouth, means for locking the brush from adjustment on the frame when the frame and brush 125 are in the hood.

2. In a suction cleaner a hood having an open suction mouth, a removable brush carrying frame supported within the hood and a rotary brush adjustably mounted on the frame within the hood adjacent the mouth, 130

means for locking the brush from adjustment on the frame when the frame and brush are in the hood, said frame having members adapted to yield to permit the 5 brush adjustment and to be held from yielding by the hood when the frame is in position therein.

3. In a suction cleaner a hood having an open suction mouth, a removable brush carrying frame supported within the hood and a rotary brush adjustably mounted on the frame within the hood adjacent the mouth, means for locking the brush from adjustment on the frame when the frame and 15 brush are in the hood, and means for yielding holding the frame in the hood.

4. In a suction cleaner a hood having an open suction mouth, a removable brush carrying frame supported within the hood and a rotary brush adjustably mounted on the frame within the hood adjacent the mouth, means for locking the brush from adjustment on the frame when the frame and brush are in the hood, and means for yielding 20 holding the frame in the hood, comprising a ledge projecting inwardly along one side of the suction mouth and a yielding member on the frame.

5. In a suction cleaner the combination of 30 a hood having an open mouth, with a removable brush carrying frame adapted to be supported in said hood and a rotary brush mounted in said frame and spring means for holding the frame in position in 35 the hood.

6. In a suction cleaner the combination of 40 a hood having an open mouth, with a removable brush carrying frame adapted to be supported in said hood and a rotary brush mounted in said frame and guard fingers mounted on said frame extending across the open mouth adjacent the brush.

7. In a suction cleaner a hood having an open suction mouth, a removable brush carrying frame, guard fingers projecting therefrom and extending across the open mouth and yielding releasable means for holding the frame removably within the hood, a rotary brush mounted on the frame adjacent 50 the guard fingers and located in the open mouth.

8. In a suction cleaner the combination of 55 a hood having an open mouth with a removable brush carrying frame adapted to be supported in said hood and a rotary brush removably mounted in said frame, guard fingers mounted on said frame and extending across said open mouth, said frame mounted so that it can be moved outside the 60 hood through the mouth to permit adjustment of the brush and means for holding the frame in position within the hood.

9. In a suction cleaner the combination of 65 a hood having an open mouth with a removable brush carrying frame consisting

of a bar with end pieces, means for mounting the brush in the end pieces and means for holding the frame in the hood and guard fingers which project from the bar across the mouth.

70

10. In a suction cleaner the combination of 75 a hood having an open mouth with a removable brush carrying frame consisting of a bar with end pieces, means for mounting the brush in the end pieces, means for holding the frame in the hood, said mouth provided with a ledge upon the inner side of which the bar rests when the frame is in position.

11. In a suction cleaner the combination 80 of a hood having an open mouth with a removable brush carrying frame consisting of a bar with end pieces, means for mounting the brush in the end pieces, means for holding the frame in the hood and guard 85 fingers which project from the bar across the mouth, said mouth provided with a ledge upon the inner side of which the bar rests when the frame is in position.

12. In a suction cleaner the combination 90 with a hood having an open mouth of a removable brush carrying frame supported in said hood and a rotary brush mounted in said frame, a flange on one side of the open mouth of the hood and located in the plane thereof, the brush carrying frame being adapted to bear against such flange.

13. In a suction cleaner the combination 95 with a hood having an open mouth of a removable brush carrying frame supported in 100 said hood and a rotary brush mounted in said frame, the ends of the frame being in frictional contact with the ends of the hood, a flange on one side of the open mouth of the hood and located in the plane thereof, 105 the brush carrying frame being adapted to bear against such flange.

14. In a suction cleaner a hood having an open suction mouth, in combination with 110 a brush carrying frame comprising two opposed brush supporting plates, a spring bar connecting them, a brush mounted for rotation on them, and means for removably holding the frame in position in the hood.

15. In a suction sweeper a hood having 115 an open suction mouth, in combination with a brush carrying frame comprising two opposed brush supporting plates, a spring bar connecting them, a brush mounted for rotation on them, fingers projecting outwardly 120 from the bar at one side of the brush perpendicular to the plane of the axis of rotation thereof and means for removably holding the brush carrying frame in position in the hood with the fingers extending across 125 the open mouth.

16. In a suction cleaner a hood having an open suction mouth, in combination with a brush carrying frame comprising two opposed brush supporting plates, a spring bar 130

connecting them a brush mounted for rotation on them, and means for removably holding the frame in position in the hood, flanges extending inwardly on both sides 5 of the open mouth, the frame being adapted to rest against one of them and yielding means for holding the frame against one of the walls of the hood said means being in line with the other flange.

- 10 17. In a suction sweeper a hood having an open suction mouth, in combination with a brush carrying frame comprising two opposed brush supporting plates, a spring bar connecting them, a brush mounted for rotation on them fingers projecting outwardly 15 from the bar at one side of the brush per-

pendicular to the plane of the axis of rotation thereof and means for removably holding the brush carrying frame in position in the hood with the fingers extending 2 across the open mouth, flanges on both sides of the suction mouth, said fingers being of such length as to substantially bridge the space between the inner edges of said flanges.

In testimony whereof, I affix my signature in the presence of two witnesses this 29th day of May, 1917.

HERBERT W. HOOVER.
